(57) CLAIM

The ornamental design for a string instrument attachment, as shown and described.

DESCRIPTION

FIG. 1 is a reduced-scale, front right perspective view of the string instrument attachment showing my new design; FIG. 2 is a reduced-scale, right, rear perspective view thereof;

FIG. 3 is a left side view thereof;

FIG. 4 is a front view thereof, the undisclosed rear view being a mirror image of front view thereof;

FIG. 5 is a right side view thereof;

FIG. 6 is a top view thereof; and,

FIG. 7 is a bottom view thereof.

The broken lines represent the portions of the design that form no part of the claim.
